UNITED STATES PATENT OFFICE

HANS C. BEHR, OF SCARSDALE, NEW YORK

CENTRIFUGAL DRIER

Application filed August 23, 1928. Serial No. 301,478.

This invention relates to centrifugal driers having a continuously running basket intermittently charged and discharged, a charge to be treated being admitted to the continuously rotating basket of the drier by automatic means, while the discharge of the dried solids is also performed automatically.

The drier basket receives a measured charge from a metering chamber connected with a larger supply like the mixing tank used with sugar centrifugals. To obtain as much capacity as is possible with a given apparatus the metering chamber must be filled and emptied quickly, and this is effected in one form of my invention by filling the metering chamber by suction and by discharging it either by means of compressed air or by steam pressure.

A further feature of the present invention is the uniform distribution of the mixture being treated on the circular screen of the drier, so as to keep the system in balance.

A still further feature of my invention is the utilization of centrifugal force stored in the treated material to aid in its discharge from the machine at the proper time. In this form the discharge is initiated and maintained by inclined scrapers, which are rotated relatively to the basket containing the material only during the discharge period, but which are not effective for discharge during the charging, purging, washing and final drying periods by being then rotated in unison with the basket and material, such variation in rotation being caused to take place automatically. To effect such relative rotation, a device working somewhat after the manner of a friction clutch is employed.

The following is a list of the illustrations to which reference will be made in these specifications:

Figure 1 is a sectional elevation of apparatus arranged for carrying out the process of my invention with a continuously running separating element.

Fig. 2 is a plan of the lower part of the apparatus shown in Figure 1.

Fig. 3 is an enlarged partial sectional elevation of the separating element shown with other elements in Figs. 1 and 2.

Fig. 4 is an under side view of the upper part of the element shown in Fig. 3.

Fig. 5 is an elevation, partly in section, of the discharging element shown entirely in section in connection with other elements in Figure 1.

Fig. 6 is an end elevation of the means for diverting the dilute liquid to a different receptacle from that for receiving the pure liquid.

Fig. 7 is an enlarged sectional elevation of the apparatus for timing and automatically controlling the carrying out of the various operations of my process.

Fig. 8 is a sectional elevation of part of the apparatus shown in Fig. 7 taken at right angles thereto.

Fig. 9 is a variation of the apparatus shown in Figure 1.

Referring to the drawings, 1 is the circular frame of the machine, having two opposite outward extending passages 2 for access to the interior and for the passage of belts driving the pulleys 3 and 4, these passages being framed by the laterals 5 and the top 6. 75 The base 7 of the frame has the central opening 8 closed by the circular base plate 9 integral with the step bearing 10 for the lower end 11 of the basket spindle 12. At 13 the spindle 12 is shown reduced in diameter for 80 the pulley 3 which is held in place rotatively by the feather 14 and against the shoulder 15 by the nut 16.

Spindle 12 is shown mounted in the quill 17 and as being free to rotate therein. The upper end of the quill 17 is mounted in the bearing 18 integral with the cap plate 19, the outer flange 20 of which is secured by bolts 21 to the upper inner flange 22 of the frame 1. Below the bearing 18 the quill 17 is loosely 90 fitted into the sleeve 23 of the pulley 4. A screwed collar 24, secured by set screw 25, holds the sleeve 23 in place vertically. The pulleys shown as 3 and 4 are driven in the same direction, but at somewhat different 95 speeds, by belts not shown.

At its lower reduced end 26 the quill 17 has fitted around it the hub 27 free to slide vertically on the portion 26, but secured against rotation by the feather 28. The upper end of 100

the hub 27 is integral with the friction cone 29 adapted to engage in frictional driving contact with the inner correspondingly coned surface of pulley 4. The lower end of the hub 27 is integral with the oppositely tapered friction cone 31 and is adapted to engage the inner coned surface 32 of the pulley 3. Hub 27 has a circumferential groove 33 between the friction members 29 and 31, into which is fitted loosely the collar 34 having at opposite sides trunnions 35 which engage with suitable holes in the double lever 36 pivoted with a pin 37 to bosses 38 integral with the frame 1. The other end of the lever 36 is connected by a pin 39 to the double link 40, by which it may be actuated to move the cone hub 27 vertically so as to engage either the friction cone 29 with the pulley 4, or the friction cone 31 with the pulley 3. In this way the quill 17 will be rotated in unison with the shaft 12 through the pulley 3, when the lever 36 is forced downward, and will be rotated in unison with the pulley 4 rotating at a different rate from pulley 3 when the lever 36 is pulled upward, the opening 41 in the frame 1 permitting such movement of the lever 36.

At its upper end the shaft 12 is formed with a flange 43 to which is secured the conical equalizing basin 44 (shown enlarged in Fig. 3) by the bolts 45. The upper edge of the basin 44 is integral with the downwardly extending cone 46, which in turn is made integral with the conical basket 47 through the ribs 48 and bolts 49 (see Fig. 4). Outwardly, beyond the ribs 48, the basket 47 has numerous grooves 50 leaving between them the narrow ribs 51, and connected at the inner and outer ends by circular grooves 52 and 53. The ribs 51 serve to support the conical screen 54, the inner edge 55 of which is bent into the circular groove 56 and secured therein by the strip 57. The outer edge 58 of 54 extends into the circular recess 59 in the lower face 45 of the outer flange 60 of the basket 47. Some of the grooves 50 are extended outwardly through the flange 60 as at 61, thereby serving as outlets for the liquid driven through the screen 54 into the radial grooves 50 and circular groove 53. The outer flange 60 is secured by the bolts 62 to the flange 63 of the inwardly coned ring 64, against which the material under treatment is pressed by centrifugal force.

55 The quill 17 at its upper end is integral with the disc 65, which at its outer edge 66 is inclined downwards so that its upper surface 67 is about parallel, though not necessarily so, to the surface of the screen 54, leaving a space 68 between the screen 54 and the edge 66.

Between the periphery of the edge 66 of the disc and the conical ring 64 there is a space 69 occupied by the inclined scraper blades 70 which are fixed to the edge 66 but are

free to move over the inner surface of the ring 64 and that of the screen 54.

The suitably inclined blades 70 when rotated relatively to the screen 54 and the ring 64, as will be the case when the cone 29 is driven by the pulley 4 at a slower rate than the screen 54 driven by pulley 3, will act to crowd the material resting against the inner surface of the ring 64 downwardly and inwardly causing it to escape at its lower edge 76 where centrifugal force drives it outwardly and against the stationary conical ring 77. Ring 77 diverts the discharge downwardly outside of frame 1, such discharge being guided to opposite sides by the inclined chutes 78. The material removed by the blades 70 from the outer end of the space 68 under the screen 54 will be followed up and replaced by the centrifugal action of the material behind it. The slope of the screen is such that the frictional resistance to movement of the dried material is overbalanced by the centrifugal force driving it outwardly. When all of the material in the space 68 and on the ring 64 has been discharged, cone 29 is released from the pulley 4 and the cone 31 is engaged with the pulley 3 by the automatic means to be described further on, causing the blades 70 to rotate now in unison with screen 54 and ring 64, and thus to become inactive.

Near its upper end the frame 1 is shown provided with a number of brackets 79 which support the base 80 of the fixed cylindrical curb 81, the outer edges of these brackets fitting inside the lugs 82 for the purpose of centering. Integral with the base 80 are two cylindrical walls 83 and 84. The annular space 85 outside these walls forms the catchment basin for the pure liquid expelled centrifugally from the mixture in the space 68 through the screen 54 and out through the passages 50 and 61, from which it is thrown out above the conical deflecting ring 86 against the curb 81 and gathered in the space 85 to be drawn off through the pipe 87. The conical ring 86 is automatically lifted at the conclusion of the pure liquid period of extraction by means to be described further on, to the position indicated by broken lines. The remaining syrup adhering to the solids and diluted with water or other liquid in a spray from the pipe 88 and now issuing from the passages 61 is caught on the under side of the conical ring 86 and diverted downwards along its cylindrical lower extension 89 into the catchment space 90 from where it is drawn off through a pipe 91.

The curb 81 is formed at its upper edge with an inwardly extending annular flange 92, to which two channel beams 93, 93 are secured at their ends by bolts and forming together a diametral girder across the curb 81 while leaving an open space between them. At the middle of this girder, so as to be truly

central with the axis of the machine, is mounted the mixture feed tube 96 secured with its rectangular flange 97 to the lower side of the beams 93 by bolts. The lower end 5 of the feed tube 96 is formed with an inwardly thickened edge 99 bored conical below to form a seat for the conical valve 100, having an upwardly extending stem 101 guided in the hub 102 integral with tube 96 through the 10 ribs 103. The valve 100 is held to its seat by the spring 104 suitably compressed against the hub 102 by jamb nuts at the upper end of the stem.

Feed tube 96 is connected at its upper end 15 through the elastic extension 106 with the outlet of the conical bottom 108 of the charge metering chamber 109, which is rigid with the mixing tank 110 suspended from the structure above the machine.

Chamber 109 communicates with the tank 110 through an opening 111 at some height 20 above its bottom and out of range of the rotating stirrer arms 112. Foreign heavy material will then settle to the bottom of the 25 tank 110 whence it may be periodically removed. Light floating coarse material is prevented from entering the chamber 109 by the screen 113. At the opening 111 a plate 114 is clamped between the inclined internal 30 flange of the chamber and the side of the tank 110 by suitable bolts. On the side adjacent the chamber 109 the plate 114 serves as seat for a flap valve 118, held to its seat by a weight 119 acting on it through a lever 120 35 pivoted to the fulcrum support 122 carried by the valve plate 114. The valve 118 may be prevented from opening, so as to act as a stop valve, by running down a screw 123 tapped into a boss on the head 125 of chamber 109.

An opening 126 through the valved fitting 127 affords communication of chamber 109 40 with either a partial vacuum or a source of moderately compressed air or light steam pressure. When in communication with a 45 vacuum, valve 118 will be forced open by the joint action of atmospheric excess over the partial vacuum and the head above the valve 118 of the mixture in the tank 110, so that the mixture will rapidly fill the chamber 109. The vacuum, though not always necessary, ensures quick filling of the chamber 109, and is therefore specially adapted when the mixture contains a viscous liquid and when 50 the mixture in 110 stands at only a small height above the valve 118. To prevent the mixture from entering the opening 126, the valve 128 is raised through a rod 130 by a float 129 to close the opening 126, the rod 55 being guided above the valve 128 by a bored boss 131 of the fitting 127, and below the float 129 by a bracket 132 in the side of the chamber 109. The source of vacuum will thus be 60 shut off, permitting the valve 118 to be again closed by the weight 119.

The spring 104 which holds the outlet valve 100 to its seat is sufficiently compressed to prevent the opening of the valve by the mere weight of the mixture above it. To effect a rapid evacuation of the metering chamber 70 and a quick filling of the space under the screen 54 in the machine, steam or compressed air is admitted to the metering chamber through the opening 126.

The timing of the cycle of alternately filling 75 and discharging the metering chamber, admitting washing fluid and diverting the diluted liquid to a different destination from that for the pure liquid, forcing cone 29 into the pulley to actuate the discharging scrapers 80 to eject the dried solids, and then connecting said scrapers to the pulley through cone 31, so as to make them inoperative during the succeeding charging, purging and washing 85 periods, is effected by the controlling apparatus shown mounted on the girders 93.

Referring first to the scraper operating means shown on an enlarged scale by Figs. 7 and 8, this consists of the cylinder 134 fixed with its basal flange 135 to the end of the 90 girders 93 by suitable bolts. A piston 137 in the cylinder 134 is preferably formed integrally with a rod 138 passing through the stuffing box at the base of the cylinder. A fixed continuous pressure is maintained in 95 the annular space between the rod 138 and the bore of the cylinder through a port 141 from a pipe 142. The lower end of the rod 138 is pivoted to the upper ends of the links 100 operating the lever 36, as before described. It will thus be seen that when there is only atmospheric pressure above the piston 137, the much higher pressure effective in the 105 space below the piston keeps it near the top of the cylinder and the cone 29 in gear with the pulley 4, thus causing a difference in rotation between the basket 47 and the scrapers 70, so as to effect discharge of dried solids, 110 as before described. To depress the piston 137 so as to force the cone 31 into gear with the pulley 3, causing unison of rotation of the scrapers 70 with the basket 47, as required during the charging, purging and washing 115 periods, pressure from the pipe 142 is admitted to the space above the piston 137 through a channel 144 in a valve chest 145 secured to the top of the cylinder 134. The 120 excess of pressure due to the difference of areas under pressure above and below the piston will force it down. To cause the piston to rise again so as to release the cone 31 from the pulley 3 and engage the cone 29 with the pulley 4, the pressure fluid above the 125 piston 137 is exhausted to atmosphere.

The valve chest or chamber 145 is shown 130 extended to the right of the cylinder 134 in Fig. 7, containing, besides pressure admission and outlet valves for operating the piston 137, the pressure admission and outlet valves for controlling the filling and dis- 135

charge of the metering chamber, and also the wash water controlling valve 171. The valve 148, nearest to the cylinder 134, when lifted off its seat 149 against the spring 150 affords communication with atmosphere through the channel 144. Above the extended channel 144 and to the right of a valve 148 is the pressure chamber 151, supplied with compressed air or steam from some convenient source through the pipe system 142, 152 entering at 153. The admission valve 154 closes the port 155 by the pressure above it and that of spring 156. When the valve 154 is lifted off its seat the pressure enters the channel 144 and acts to depress the piston 137, putting the cone 31 in gear with the pulley 3, as previously described.

The metering chamber through the fitting 127 is in permanent communication with the channel 157 in the valve chest or chamber 145, the communicating pipe 158 being made of flexible material to permit moderate relative displacement between the metering chamber and the valve chest. In the bottom of the channel 157 is fixed a small vacuum chamber 159 communicating through a lateral opening 160 and a pipe 161 with a suitable partial vacuum producing source. The upper opening 162 of this small vacuum chamber is controlled by a valve 163 held to its seat by the pressure of a spring 164. When the valve 163 is lifted off its seat, vacuum is established in the channel 157 and through the communicating pipe 158 in the metering chamber 109, so that the valve 118 is forced open and the mixture to be treated enters to fill the metering chamber as previously described.

Between the pressure chamber 151 and the channel 157, beneath it, is a valve port 173 controlled by the pressure admission valve 165, held to its seat by the pressure in the chamber 151 and the spring 166. With the valve 165 lifted, pressure is admitted through the channel 157 and connection 158 by the port 126 onto the top of the mixture in the metering chamber, thereby forcing open the outlet valve 100 and rapidly discharging the chamber. The mixture charge flowing down into the rotating equalizing cone 44 has rotation imparted to it by frictional contact, so that it flows outwardly and upwardly over the edge of the cone into the conical basket 47 and ultimately fills the space 68 under the screen 54. While being rotated with the cone 44 any circumferential inequality of the outwardly flowing sheet of the more or less fluid mixture is corrected by its tendency to assume an equipotential surface under centrifugal force in a similar manner in which gravity acts to level the surface of liquid and semiliquid substances.

At the extreme end of the valve chamber 145 is a water valve chamber 167 supplied with water under moderate pressure through

a pipe 168, and communicating through a port 169 with a chamber 170 beneath, normally closed off from the valve chamber 167 by a valve 171 under pressure of water and that of a spring 172. When the valve 171 is lifted, water flows through the port 169 into the chamber 170 and out through the pipe 88 into the cone 44, which imparts to it rotary motion and equally distributes it around the periphery in a similar way as previously described for the mixture.

The extreme end of the valve chamber 145 has a flange 174 bolted to a vertical frame 175, the lower flange 176 of which is bolted to the double girder 93.

The opening of each of the valves 148, 154, 163, 165 and 171 is accomplished through the lifting rods 177, 178, 179, 180 and 181, actuated respectively by cams 182, 183, 184, 185 and 186, fixed on a cam shaft 187 mounted in bearings 188, 189 and rotated from some convenient source of power by such means as a pulley 190. The cams are adjusted circumferentially to cause lifting of each of the valves in proper succession and at the proper time intervals required for the series of functions of charging, purging, washing and discharging, and such adjustment is made variable to suit conditions as by the set screws 191 in the hubs 192 of the cams.

The cams 182 to 186 act on the rods 177 to 181 through rollers 193, mounted in a slot of the blocks 195. The rods are adjustably screwed with their lower ends into the upper ends of the blocks and secured by jamb nuts. The blocks 195 are guided vertically in rectangular holes in the guide bar 198, supported from the valve chamber 145 by the distance pieces 199 and bolts 200. The rod 177 has its upper end guided in a boss integral with the valve seat 149. The upper ends of the rods 178, 180 and 181 are guided vertically in the bores of the bonnets 203, 204 and 205, fitted and secured to the lower face of the valve chamber 145, the bonnets having stuffing boxes at their lower ends. The rod 179 has its upper end guided in a stuffing box at the lower end of the vacuum chamber 159. The rollers 193 are kept in contact with their respective cams by springs 150, 156, 164, 166 and 172 by pressing down on their respective valves.

For the purpose of raising the conical deflector ring 86, previous to admitting wash water by the valve 171, the deflector has fixed to it the lugs 208 by which it is suspended through rods 209 from the ends of levers 210, 211, 212 and 213, the rods having their jaw ends pivoted to the ends of the levers. The levers are secured with their hubs on the ends of two parallel rock shafts 216 which are carried in the open top bearings 217 fixed with their shanks into the girders 93. The lever 212 has rigid with it an opposite arm 219, the end of which is loosely pivoted into

the jaw of an arm 221 opposite to and rigid with the lever 213, so that the ends of the levers 212 and 213 must rise and fall together by equal amounts in adjusting the deflector 86. The other levers 210 and 211 will also move in unison with levers 212 and 213 by the same amount, since they are rigidly connected to the same shafts 216. Movement is imparted to the system of levers 210, 211, 212 and 213 by a cam 222 mounted on the shaft 187 acting downwardly on a roller 223 pivoted in the jaw of an arm 225 rigid with the lever 210.

The machine illustrated by Fig. 9 differs from Figure 1 only in that the pulley 4 with its long sleeve hub 23 of Fig. 1 is replaced in Fig. 9 by the upward continuation of hub 27, which is integral at its upper end through the disc 300 with the friction cone 301, adapted to engage with the fixed friction cone 302, which is integral with plate 19.

Starting at the point when the metering chamber 109 is empty and about to receive a charge, the operation of the apparatus described, and of the process carried out by its aid, is as follows: At this point the cam 184 is just lifting the vacuum valve 163 off its seat on the small vacuum chamber 159, which is connected to some suction source through the pipe 161 so that a partial vacuum will be established in the space 157 and, through the pipe connection 158, in the metering chamber 109. Such vacuum causes the supply valve 118 to be opened and the weight 119 to be lifted by the excess of atmospheric pressure acting on the supply of mixture in the tank 110 plus the pressure due to the height of the mixture in the tank above the opening 111. Mixture then flows from the tank 110 into the chamber 109 and on reaching the float 129 raises the latter sufficiently to force the valve 128 against its seat, thereby shutting off the connection with the suction source. After this the mixture still continues to rise to a point at which the air (or other gas) above it is sufficiently compressed to balance the pressure in the tank 110 above the supply opening 111. The supply valve 118 is then closed by the weight 119. The cam 184 in its rotation now permits the spring 164 to close the vacuum valve 163, and thereafter the pressure valve 165 is opened by the rotation of the cam 185, thereby permitting air or other gas under pressure to enter the space 157 and the chamber 109. Such pressure is sufficient to overcome the force of the spring 104 holding the valve 100 to its seat, so that this valve is held open and permits the metered mixture charge to be quickly expelled from the chamber 109 and to flow down into the rotating conical equalizing basin 44.

The conical surface of the basin 44 by frictional contact imparts to the mixture its own rotation and as the mixture is driven outwardly and upwardly by centrifugal force, it is caused to assume a truly centered surface

of rotation, in other words, an equipotential surface about the axis of rotation. And since the basin has also a truly centered surface of revolution, the mixture passing over it arrives at its outer edge in the form of an annular zonal stream of practically uniform thickness, so that balanced distribution of the mixture is obtained.

From the outer edge of the basin 44 the mixture is projected further out between the ribs 48 onto the inner surface of the basket 47 and beyond over the screen 54, partially piling up against the inner surface of the conical ring 64. The inner portion of the ring of mixture, constituting the complete metered charge from the chamber 109, slopes down from a thin edge at the top according to the angle of repose of the material as indicated at 75 in Fig. 1. During and after the deposition of such charge, centrifugal force expels liquid from the mixture through the screen 54, which liquid flows outwardly through the grooves 50 and 61, is projected from the edge 63 against the curb 81, flows down into the annular space 85 and is conveyed away through the pipe 87.

In many cases it is not practicable, or even possible, to eliminate by centrifugal force all of the pure liquid held back in between the solid grains in the mixture by capillary force. It then becomes necessary to dilute the remaining, generally valuable, liquid with water or other diluent to enable its removal by centrifugal action and to obtain the desired degree of purity of the solid part of the mixture. Following, therefore, the period of purging of pure liquid, water is admitted into the basin 44 from the pipe 88 (Fig. 1), the water admission valve 171 having been lifted off its seat at the proper moment by the rotation of the suitably adjusted cam 186. The water received in the basin is given rotation through frictional contact with the metal of the basin and is equally distributed in its outward passage by centrifugal force in the same way as described for the mixture charge, and is projected further outwardly onto and into the annularly deposited mixture charge under the screen 54. In passing through this deposit the water dilutes and washes away the pure liquid films sticking to the solid grains. The dilution passes through the screen 54 and through the channels 50 and 61 and is thrown off at the edge 63 like the pure liquid as before described. Previous to the admission of water through pipe 88 the deflector cone 86 has been raised to the position indicated in broken lines in Fig. 1, so that the outward stream of diluted liquid is caught on the under side of the cone 86 and is thereby diverted down into the annular space 90 from which it is led away through the pipe 91. The raising and lowering of the cone 86 is effected at the proper times through the system of levers 210, 211,

212, 213 by the rotation of the suitably adjusted cam 222 acting down on the roller in the jaw of arm 225 rigid with the lever 210. After the conclusion of the washing period the cone 86 is again permitted to sink to its lower position through the rotation of the cam 222.

After a short period sufficient for the centrifugal air drying of the solids under the screen 54, these solids are ready to be discharged. During the above described operations of depositing the mixture in the basket, of expelling the pure and the diluted parts of the liquid content and of air drying the solids, the discharge blades 70 are imbedded in the charge and rotating in unison therewith and with basket 47. Such unison of rotation was secured by the cone 31, which was shown in the description of the apparatus to be rotatively rigid with blades 70, being forced into frictional contact with the conical bore of the pulley 3 rigid with the basket 47. The required axial downward movement of the cone 31 on the sleeve 17 was caused to take place at the proper moment by the suitably adjusted rotating cam 183 which, through the rod 178, lifted the valve 154 off its seat to admit air or other fluid under pressure on top of the piston 137, thus overbalancing the continuously acting pressure in the annular space 140 beneath it, so as to force it down and with it the lever 36 pivoted to the ring 34 encircling the sleeve 27 rigid with the cone 31.

To cause the discharge of the completely dried solids from the basket 47 and cone 64 the friction cone 31 must be withdrawn from the pulley 3 and the upper cone 29, rigid with the cone 31 through the sleeve 27, must be raised and forced into frictional contact with the conical bore of the pulley 4 which is rotated at a different, preferably slower, rate than that of pulley 3 with basket 47. Such raising of the sleeve 27 with the cones 31, 29 is performed by the upward movement of the piston 137 coupled to the sleeve through the links 40 and the lever 36, after the pressure admission valve 154 has been allowed to be closed by the spring 156 through the rotation of the cam 183, and after the compressed air above the piston and in the space 144 has been allowed to escape by the raising off its seat of the exhaust valve 148, accomplished by the rotation of the suitably adjusted cam 182. The different rate of rotation from that of the basket 47, imparted by the pulley 4 to the blades 70, causes the latter, which are suitably inclined to the path of rotation, to scrape the dried solids downwardly and inwardly over the inner surface of the cone 64 and off at its lower edge 76. The solids fly off outwardly from this edge against the inner surface of the stationary cone 77, which diverts them down outside of the frame 1 onto the inclines 78,

which in turn divert them to two opposite sides of the machine onto suitable gathering or conveying devices. The solids under the screen 54, inside of those being removed by the scraper blades 70, are driven by the excess of the centrifugal force stored in them over their frictional resistance to outward movement over the screen to continually follow up so as to fill up the spaces as they are emptied by the scrapers until all the material under the screen has been discharged.

After the solids have been discharged, the cam 182 by its rotation permits the valve 148 to be closed by its spring 150, while the cam 183 acts immediately thereafter to raise the valve 154, so that pressure from the space 151 enters again into the channel 144 and over the piston 137 and, overbalancing the pressure on the smaller area beneath it, drives the piston and the lever and the cone 31 down, so that the latter is again in frictional coupling with the pulley 3 and the blades 70 are again rotating in unison with the basket 47. The cycle of operations is thus complete and the machine ready to receive the next charge now held in the metering chamber, into which it was admitted during the time occupied by other operations of the machine.

In the case of Fig. 9 the blades 70 and the cone 301 rigid therewith are only retarded and not stopped by the frictional engagement with the fixed cone 302, the retardation being just sufficient to effect the complete discharge of the dried solids.

It is to be understood that the centrifugal machine shown in the drawings, while being the preferred form, is illustrative of my invention and that changes may be made within the scope of the claims without departing from the spirit of the invention.

Having described my invention, I claim and desire to secure by Letters Patent:

1. In a centrifugal drier for separating liquid from solid aggregate, the combination with a conical basket so sloped that the material being treated, if unobstructed, would be moved outwardly over its inner surface by centrifugal force, there being formed on the inner surface of the basket numerous substantially radial ribs, and passages communicating with the spaces between the ribs and passing through the basket to its periphery, and means adapted to continuously rotate the basket, of a screen bedded on the tops of the ribs, a smooth retaining cone rigid with and coned inwardly from the basket, a discharger consisting of a disc and blades carried upon its periphery and adapted to move the material being treated inwardly over the inner surface of the retaining cone, and means for selectively causing the discharger to rotate either in unison with or at a different rate of speed from the speed of rotation of the basket.

2. In a centrifugal drier for separating liquid from solid aggregate, the combination with a conical basket so sloped that material being treated, if unobstructed, would be moved outwardly over its inner surface by centrifugal force, there being formed on the inner surface of the basket numerous substantially radial ribs, and passageways communicating with the spaces between the ribs and 5 passing through the basket to its periphery, a shaft upon which the basket is mounted, and means adapted to continuously rotate the shaft, of a screen bedded on the tops of the ribs, a smooth retaining cone rigid with and 10 coned inwardly from the basket, a discharger consisting of a disc and blades carried upon its periphery and adapted to move the material being treated inwardly over the inner surface of the retaining cone, a sleeve loosely 15 surrounding the shaft and fast with the disc, and means for selectively causing the sleeve to rotate either in unison with or at a different rate of speed from the speed of rotation of the shaft. 20
- 25 3. In a centrifugal drier for separating liquid from solid aggregate, the combination with a basket, a shaft carrying the basket, means for continuously rotating the shaft, a friction clutch surface carried by the shaft, 30 a discharging device furnished with scrapers for removing the solid material from the basket, a sleeve loosely mounted on the shaft and carrying the discharger, a second sleeve loosely surrounding the first sleeve, a friction 35 clutch surface rigid with the second sleeve, means for rotating the second sleeve at a different rate of speed than the rotation of the shaft, a third sleeve rotatable with and axially movable on the first named sleeve, and 40 friction clutches carried by it at its respective ends, one of said clutches being adapted to couple by axial movement with the first named clutch surface, and the other by opposite movement adapted to couple with the 45 second named clutched surface. 50
4. In a centrifugal drier for separating liquid from solid aggregate, the combination with a basket, a shaft carrying the basket, means for continuously rotating the shaft, a friction clutch surface carried by the shaft, 55 a discharging device furnished with scrapers for removing the solid material from the basket, a sleeve loosely mounted on the shaft and carrying the discharger, a second sleeve loosely surrounding the first sleeve, a friction 60 clutch surface rigid with the second sleeve, means for rotating the second sleeve at a different rate of speed than the rotation of the shaft, a third sleeve rotatable with and axially movable on the first named sleeve, and friction clutches carried by it at its respective ends, one of said clutches being adapted to couple by axial movement with the first named clutch surface, and the other by opposite movement adapted to couple with the 65 second named clutched surface. 70
